UNITED STATES PATENT OFFICE.

HARRY HARDWICK, OF PHILADELPHIA, PENNSYLVANIA.

DEVICE FOR CORRECTING IMPROPER REGISTRY OF PARTY-COLORED WARP-THREADS.

SPECIFICATION forming part of Letters Patent No. 691,136, dated January 14, 1902.

Application filed June 8, 1900. Serial No. 19,539. (No model.)

To all whom it may concern:

Be it known that I, HARRY HARDWICK, a citizen of the United States, residing in Philadelphia, Pennsylvania, have invented certain 5 Improvements in Devices for Correcting Improper Registry of Party - Colored Warp-Threads in Textile Machinery, of which the following is a specification.

My invention consists of certain improvements in or modifications of the devices for 10 correcting improper registry of party-colored warp-threads in textile machinery set forth in my application for patent, Serial No. 14,285, of 1900, filed April 25, 1900, the objects of my 15 improvements being to so construct the mechanism that the tightening or slackening of the threads can be controlled more readily than before and to provide means for intentionally deranging the threads, so as to produce 20 lines or stripes of color across the same, and thus permit departures from a true position to be more readily noted.

The improvements have been devised with especial reference to the application of the 25 invention to a warp-beaming machine, and in the accompanying drawings—

Figure 1 is a longitudinal section of the mechanism. Fig. 2 is an enlarged view of an escapement device forming part of the same. 30 Figs. 3 and 4 are diagrams illustrating the purpose of one of the features of the invention, and Fig. 5 is an enlarged front or face view of part of the machine.

In a suitable framework 1 is mounted the 35 shaft or spindle of the warp-beam 2, said frame also carrying bearings for a number of guide-rolls 3, 4, 5, 6, 7, 8, 9, and 25 and being provided with guides for two sets of deflector-bars 10 and 11, each set having one 40 bar for each thread of the warp, the bars 10 being disposed between the rollers 6 and 7 and the bars 11 occupying a position between the rollers 8 and 9 and each of said bars having an antifriction-roller 12, around which 45 passes the thread which it is to control.

The threads are drawn from spools on a spool-frame 13, suitably located in respect to the frame 1, and said threads pass first to a suitable tension device, such as the roller 9, 50 and a roller 14, which presses upon the roller 9 with such force as to impart the proper tension to the threads passing between the two

rollers. Set-screws acting upon the bearings of either roller may be used to cause this pressure of the rollers against one another. 55

From the rollers 9 and 14 the threads pass to and around the antifriction-rollers 12 of the bars 11, thence to and around the roller 8, thence to and around the roller 7, thence to and around the antifriction-rollers 12 of the bars 10, thence to and around the rollers 6 and 25, thence to and around the roller 5, thence down to and around the roller 4, thence to and around deflecting bars or rollers 15, thence to and around the roller 3, and finally 60 to the beam.

The arrangement of the bars 10 in respect to the pair of rollers 6 7 and of the bars 11 in respect to the pair of rollers 8 9 is similar to that set forth in my former application, said 70 bars having movement between the rollers in a plane at right angles to the axes of said rollers; but in the present instance the roller 12 of each bar 10 is near the lower end of the same, while the roller 12 of each bar 11 is near 75 the upper end of the same, and each bar operates by a downward movement, whereby the bars 10 serve to take up slack in or tighten 80 the threads upon which they act, while the bars 11 serve to let out or slacken the threads subjected to their action. This action differs 85 from that of the device of the former application in that in the latter tightening of either thread was effected by movement of its deflector-bar in one direction and slackening of the thread by movement of its deflector-bar in the opposite direction, the use of two independent sets of bars in the present machine, one set intended for tightening the threads and the other set intended for slackening the same, being due to the fact that I 90 desire to control said bars by means of escapement mechanism connected to a keyboard, so that the operative movement of each bar is in but one direction. Each of the bars 95 has teeth for engagement with the beveled tappet 16 and straight tappet 17 of an anchor-lever 18, which has an arm 19, connected by a cord, wire, or other suitable connection 20 to one of the key-levers 21 of a keyboard located at the front of the machine, suitable 100 guide rollers or pulleys 22 being provided for the proper direction of the connections 20, when the latter are in the form of flexible

cords or wires. When, therefore, either key is depressed, the escapement-lever of its corresponding deflecting-bar will be moved, so as to carry the straight tappet 17 out of engagement with the tooth which is supported and bring the beveled tappet 16 into engagement with a higher tooth, the descent of the bar immediately forcing this upper tappet outward again owing to its beveled face, and thereby moving the lower tappet 16 into position to engage with the tooth above that with which it was formerly in engagement. The escapement device is thus self-locking in the retaining position. Pressure of a tooth upon the tappet 16 tends to move said tappet farther into engagement with the tooth, and this tendency may be restricted by a suitable stop—for instance, by a bar 26—with which the arm 19 of the escapement-lever comes into contact. Each depression of a key therefore will permit of the lowering of its corresponding deflecting-bar to the extent of one tooth, the downward movement of the bars 10 being due to their weight, which may, if desired, be assisted in any suitable way, and the downward movement of the bars 11 being due to their weight, in addition to the tension upon the warp-threads. The warp-beam 2 being rotated at any desired rate of speed, the entire series of threads, disposed closely side by side, pass from the upper roller 5 to the lower roller 4 in front of the attendant seated at the machine, who notes any tendency of either thread to move out of registry with its adjoining threads and corrects this tendency by proper movement of the bar 10 or 11 controlling said thread, movement of the bar 10 tightening the thread in case it has a tendency to creep ahead of its fellows and movement of the bar 11 slackening the thread, if it has a tendency to lag behind.

In order that the departure of adjoining threads from their proper registry may be more readily detected by the attendant, I prefer to so derange the threads as to form straight lines of color, each extending across or part way across the series, one or more of these straight lines being formed for each repetition of the pattern, so that as the lines travel from the upper roller 5 to the lower roller 4 the attendant has ample time to note and correct any defective registry of the threads. The derangement of the threads may be such as to form a single line extending entirely across the series of threads or there may be a number of shorter lines disposed in different planes. The derangement of the threads I effect by deflecting certain of the threads, or in some cases perhaps all of the threads, to a greater or less extent from a straight line before they reach the beam 2. Thus in Fig. 3 I have shown twelve threads $a b c d e f g h i j k l$, having spots outlining a rectangular figure. Certain of these threads are deflected, so as to bring spots of the threads $a b c d e h i j k l$ into line with spots of the threads $f g$, the extent of such deflection gradually

decreasing from a to e and from l to h , or, as will be evident, the reverse method may be adopted, and spots of the threads $b c d e f g$ ⁷⁰ $h i j k$ may be brought into line with the spots on the threads $a b$, the extent of deflection gradually decreasing from b to f and from k to g . This derangement of the threads, however, occurs wholly above the roller 4, the disposition of colors on the threads below the roller 3 being such as to form the desired pattern. Hence the threads all bear the proper relation to each other as they are wound upon the beam. ⁷⁵

In front of the threads as they pass from the roller 5 to the roller 4 I prefer to arrange an index-bar 23, marked or numbered to accord with each of the threads, so that the identity of any thread which is out of registry may be instantly determined and the corresponding marked, numbered, or positioned key-manipulated in order to correct such improper registry. ⁸⁵

It will be evident that the sets of bars 10 and 11 may be multiplied to any desired extent in order to avoid crowding or to provide a greater range of control of each thread, and, if desired, the bars may all be constructed, as at 10, to tighten the threads or, as at 11, to slacken the same, the use of reversely-acting bars, however, being always preferred. ⁹⁰

While the use of the keyboard is preferred because of its convenience, the escapement-levers may, if desired, be operated by other means—for instance, by direct manipulation of the connections 20, and the threads may take any desired course in their approach to the roller 4. ¹⁰⁰

As in the machine of the former application the deflecting-bars 10 and 11 may be regarded as devices for regulating the tension upon the threads in their passage from the rollers 9 and 14 to the beam 2, movement of a bar 10 increasing the tension upon its thread ¹⁰⁵ and movement of a bar 11 decreasing the tension upon its thread. ¹¹⁰

Having thus described my invention, I claim and desire to secure by Letters Patent— ¹¹⁵

1. The combination in means for correcting improper registry of party-colored warp-threads in textile machinery, of two sets of guides for deflecting the warp-threads from a straight course, one set of guides being adapted to tighten the threads and the other set to slacken the same, and each set of guides having movable elements, one for each of the threads to be controlled, and provision for varying the deflective position of said warp-controlling element of each set of guides, substantially as specified. ¹²⁰

2. The combination in means for correcting improper registry of party-colored warp-threads in textile machinery, of a set of guides for deflecting said threads from a straight course, said set of guides having for each thread to be controlled a movable element adapted to vary the extent of deflection ¹³⁰

of the thread, and escapement devices for controlling the movement of said elements, substantially as specified.

3. The combination in means for correcting improper registry of party-colored warp-threads in textile machinery, of a set of guides for deflecting said threads from a straight course, said set of guides having for each thread to be controlled, a movable element to vary the extent of deflection, escapement devices for controlling such movement of said elements, and key-levers for operating said escapement mechanism, substantially as specified.

15 4. The combination in means for correcting improper registry of party-colored warp-threads in textile machinery, of a frame carrying the spools from which the threads are drawn, a set of guides having movable elements for independently deflecting each of said threads from a straight course, means for varying the extent of deflection of each thread, and tension devices interposed between said deflecting devices and the spools, substantially as specified.

5. The combination in means for correcting improper registry of party-colored warp-threads in textile machinery, of independent and separately controllable tension devices for each of the threads to be governed, and means for deranging the threads so as to bring portions of the same which are normally out of line, into line with each other, and thereby form a stripe or band extending

across a series of threads, substantially as specified.

6. The combination in means for correcting improper registry of party-colored warp-threads in textile machinery, of independent and separately controllable tension devices for each of the threads to be governed, and an index-bar extending across the series of threads, substantially as specified.

7. The combination in means for correcting improper registry of party-colored warp-threads in textile machinery, of a frame carrying spools from which the threads are drawn, a rotatable beam upon which the threads are wound, and independent and separately controllable tension devices for each of the threads to be governed, said devices acting upon the threads in their course from the spools to the beam, substantially as specified.

8. The combination in means for correcting improper registry of party-colored warp-threads in textile machinery, of thread-controlling devices each having as elements a toothed bar, a self-locking escapement-lever therefor, and means for vibrating said lever, substantially as specified.

In testimony whereof I have signed my name to this specification in the presence of two subscribing witnesses.

HARRY HARDWICK.
